[57] CLAIM

The ornamental design for a batting order board or similar article, substantially as shown and described.

DESCRIPTION

FIG. 1 is a front elevational view of a batting order board or similar article, showing my new design.

FIG. 2 is a right side elevational view, the left side elevational view being a mirror image thereof.

FIG. 3 is a rear elevational view thereof.

FIG. 4 is a top plan view thereof; and

FIG. 5 is a bottom plan view thereof.
